5 Claims. (Cl. 200—147)

This invention relates to circuit breakers of the type provided with an arc extinguishing chamber.

Many of the known circuit breaker systems for heavy electrical load or high power duty show a lack of dynamic stability which was to be overcome by the provision of intermediary contact members which relieve the current-conductive main contact. However, these improved known devices still show certain drawbacks to be explained further below, and it is the object of the present invention to provide a circuit breaker of the above-mentioned arc-extinguishing type which does not require intermediary contact members, and has nevertheless a better dynamic stability than the known circuit breakers.

The drawbacks of the known circuit breakers provided with intermediary contact members, and the nature and advantages of the device according to my invention will now be explained in detail with the aid of the accompanying drawings in which

Figure 1 shows schematically a side view of a circuit breaker of the prior art;

Figure 2a shows schematically the current flow and arc extinguishing means in a first embodiment of the circuit breaker according to the invention in make position;

Figure 2b shows the lower part of Figure 2a, but with the circuit breaker being opened to break position;

Figure 3 is a partial schematical view in perspective of the lower portion of the embodiment illustrated in Figures 2a and 2b, but showing more structural details;

Figure 4 is a transverse sectional view in a vertical plane through Figure 3 as indicated by IV—IV in the latter figure;

Figure 5 is a partial sectional view of a somewhat different detail in the embodiment as illustrated in Figure 4;

Figure 6 is a transverse sectional view of a circuit breaker according to the invention comprising the feature illustrated in Figure 5;

Figure 7 is a schematical perspective view, similar to that of Figure 2b, but of another embodiment of the circuit breaker according to the invention;

Figures 8a, 8b and 8c show different modes of wiring the circuit breaker according to the invention in series or in parallel, adapted for direct current as well as for multiphase alternating current.

Figure 9 illustrates the arc blowing field forces generated in the region of the magnet iron system 12;

Figure 9a illustrates the stray field forces in the same region, but without the provision of a magnet iron system, and

Figure 10 diagrammatically illustrates the flow of a short circuit current dependent on time through a circuit breaker according to the invention.

In the circuit breaker of the prior art as illustrated in Figure 1, reference numeral 21 designates the main contact bearing, for instance, the usual silver lining, 22 is the auxiliary or arc-forming contact, 23 is the intermediary contact and 24 is the conventionally used arc-blow

2

out coil which serves to blow the arc formed between the auxiliary contact member 3 magnetically upwardly into an arc extinguishing chamber (not shown).

It is the task of the intermediary contact 23 to take over current flow from the main contact when the latter is opened so that no arc formation is to occur at the main contact and facilitate transfer of current flow to the auxiliary contact 22 at which arc formation is to occur so that only this contact is subjected to the wear by burning caused by the arc.

As the intermediary contact 23 opens this transfer of current flow is to occur to the still closed auxiliary contact 22. This transfer of current flow, however, cannot be instantaneous, but is somewhat lagging in time since the inductive resistance offered in the new current path via the auxiliary contact 22 must first be overcome. This usually leads to the formation of a small arc at the intermediary contact 23 as the latter opens.

When rushes of sudden high short circuit currents occur, it often happens that the current forces are so strong as to dynamically open the intermediary contact 23 simultaneously with the main contact 21. Thereby, the current is forced to shift directly from main contact 21 to auxiliary contact 22. However, due to the blow-out coil inductivity, the current cannot flow instantaneously fully through the auxiliary contact 22, and an arc is formed at the normally arc-free main contact 21, which arc burns the contact members. The blow-out coil inductivity often becomes first effective after both main and auxiliary contacts have opened and, in turn, also causes a delay in current commutation, whereby strong welding and burning effects may occur at the intermediary contacts 23.

Such faulty operation is completely avoided in the circuit breaker according to my invention which comprises, as a main feature, a contact bridge being the movable main contact member and adapted for cooperation with a plurality of stationary main contact members and equal number of stationary auxiliary contact members.

The division into several main and auxiliary contact members and the provision of a corresponding number of parallel current paths, for instance as current conductive rails, in the bridge achieve a division of the voltage, and the general arrangement of the current path throughout the entire device is particularly favorable for a rapid and safe arc extinction.

Of further advantage in obtaining the latter goal, is the fact that, due to the division of the voltage and by distributing it over at least two or more contact places, the conventional large arc-extinguishing chamber can be subdivided into several, for instance two, three or four sub-chambers of correspondingly smaller dimensions.

The individual arc extinguishing chambers can therefore be of smaller dimensions.

In connection herewith, the dynamic contact making pressure of the contact bridge directly against the stationary contact surfaces of the circuit breaker system is increased by having the contact bridge disposed movably within the space defined by the aforesaid current-conducting rails and the stationary main contact members.

The contact pressure of the closed circuit breaker is increased whenever a sudden current rush occurs, as shall be explained in greater detail hereinafter.

It is advantageous to build the contact pairs from members of the type of multi-contact point surface contacts, as is achieved by providing at least one of the two contacting surfaces with a silver lining or plating.

The resulting great number of contact points between the surface of the stationary and the abutting surface of the movable contact member of each pair guarantees a reduction of current density at each point.

According to another important feature of the invention, the blowing of the arc formed between each auxiliary stationary and movable arc-drawing contact members into the corresponding arc extinguishing chamber is effected by a magnetic circuit closed upon itself instead of the conventional blow-out coils.

Referring now more in detail to the embodiment of a circuit breaker according to the invention illustrated in Figures 3 and 4, a casing 20 of insulating material houses the main contact, the stationary element of which is divided into two fixed plate members 2 and 2a, connected with the two parallel bus bars 25 and 25a, respectively (see Figures 2a and 2b). The movable element is formed by the above-mentioned preferably silver-plated contact bridge 1. The latter is mounted at the lower end of two electrically conductive bridge-bearing arms 3, 3a which are pivotally mounted about an axis of rotation indicated at 4 in the casing 20 by means of a shaft 5 against which they are insulated at 4a.

At one end of shaft 5 there is mounted hand lever 5a for operating the circuit breaker.

Arms 3 and 3a form at their upper ends the movable members 11 and 11a of the arc-forming auxiliary contact element of the system. These bear against the stationary contact counter members 6, 6a.

Since the contact bridge 1 and the movable contact members 11, 11a of the auxiliary arc-forming contact are rigidly connected with each other by means of arms 3, 3a, it is necessary to devise the contact members 6 and 6a resiliently, as by means of springs 7 and 7a which rest in the frame 20.

The spring means or other resilient means supporting stationary contact members 6 and 6a may be so adjusted (by conventional means not shown) that a determined contact pressure is achieved at the auxiliary and main contacts.

The pressure means which urge bridge 1 into contact with members 2 are conventional and correspond to those establishing contact pressure at the main contact shown in Figure 1 and designated as 18.

According to a slightly different embodiment illustrated in Figure 5, each of members 6 and 6a has a downwardly extending nose 6n pivotably connected by means of a pin or bolt 9 to the stationary rails 10, 10a.

The stationary support members 10 and 10a carry the fixed plate members 2 and 2a respectively of the main contact.

At the same level as the auxiliary arc-forming contact, there is provided about each set of stationary and movable contact members, for instance 6 and 11, or 6a and 11a, a blowing magnet system 12, consisting of a laminated magnetic iron core, as illustrated, for instance, in Figures 2a and 2b, which comprises and legs 12a and 12b, intermediary legs 12c and 12d, and yokes 12e and 12f.

Each of the magnetic systems closed upon themselves which are thus formed are so disposed, as illustrated in Figure 2b, that the stray field 13a and 13b, on the one hand, and 13c and 13d on the other hand, generated by the current flowing through 6 and 11 (or 6a and 11a, etc.) respectively, generate in turn magnetic flows having the same directions, respectively in the intermediary legs 12c, 12d of the magnetic system. This is indicated by the arrows at 13a, 13b and 13c, 13d. The resulting electromagnetic blowout field is intensified and concentrated in space by the laminated magnetic iron system 12.

The embodiment of the magnetic circuit shown in Figures 2a and 2b thus resembles the yoke of a three-leg transformer. The combined intermediary, or central legs 12c and 12d (which may also be an integral part) divide the rectangular magnetic core into two closed units each having a window-like opening in which one auxiliary contact system (6, 11 or 6a, 11a) is arranged.

Above each opening there is mounted one of the partial arc-extinguishing chambers 14, 14a, as shown schematically in Figure 2a.

If there are more auxiliary contacts 16a, 16b, 16c, 16d, as in Figure 7, a corresponding number of magnetic circuits 12¹, 12², 12³ and 12⁴ and a corresponding number of arc-extinguishing chambers (not shown) are provided for.

The fixed and movable auxiliary contact members of a subdivided system are connected in series as shown by arrows from main terminal (—) to terminal (+) in Figure 2b. The signs of these terminals may indicate direct current, but multi-phase alternating current may also be controlled with the circuit breakers according to the invention.

By this type of series connection current flow between one pair of auxiliary partial contacts, for instance 6 and 11, is opposite in direction to current flow between the other pair formed by members 6a and 11a. This is also illustrated by the arrows in the respective arcs 17 and 17a shown in Figure 2b.

When the circuit breaker is opened, as by swivelling lever 5a from the position shown in full lines in Figure 4, to the position shown therein in dashed lines, the oppositely directed magnetic strayfields 13a and 13b at one end, and 13c and 13d on the other end will so influence the oppositely directed arcs 17 and 17a that both arcs are driven into their respective arc-extinguishing chambers 14 and 14a.

The arrangement of the current paths as shown in Figures 2a and 2b, and also in Figure 7, provides for a very favorable blowing of the formed arcs. Due to the voltage division at the auxiliary contacts, each partial extinguishing chamber need only be dimensioned for half the total voltage, and the entire circuit breaker can be built smaller.

In Figure 7, the contact bridge comprises a bar 1c of insulating material and on the latter two contact sections 1a and 1b forming together the movable member of the main contact. The fixed element of the main contact is subdivided into four contact plates 2 and 2' connected to terminal 19, and 2a and 2a' connected to terminal 19a.

The above-mentioned auxiliary arc-forming contacts 16a, 16b, 16c and 16d consist of movable members 11a, 11b, 11c, 11d, and stationary resiliently mounted members 6a, 6b, 6c and 6d.

These members are connected with each other in two parallel series in the following order:

They could also be connected in series, as will be easily understood from Figure 7, according to the following scheme:

Each magnetic system closed upon itself may consist of a permanent magnet or an electromagnet. In the latter case coils will be disposed on the legs of the magnetic circuit.

Various possibilities of using several, for instance three

circuit breakers in a combined system are illustrated in Figures 8a, 8b and 8c.

Thus, Figure 8a shows the three circuit breakers I, II and III connected in parallel to three direct current sources. Figure 8b shows the same three devices connected in series to a single direct current source, and Figure 8c shows the three devices connected to a three-phase alternating current source.

The magnetical and electrical forces occurring during the operation of the circuit breaker according to the invention shall be explained further with the aid of Figures 2a, 2b, 7, 9, 9a and 10.

Due to the inertia of the masses of its contact system, a conventional power circuit breaker is not adapted for having its contacts open during the occurrence of the first half-wave of an eventual short-circuit current.

The time elapsing between the reaction of the excess current breaker releasing device (conventional and not shown in the drawings) but acting on shaft 4 replacing the hand lever 5a actuating the circuit breaker and the actual separation of the contact members from each other is in the order of 20 to 40 milliseconds, or about 2 to 4 half waves in the case of 50 cycle or 60 cycle alternating currents.

Since the short circuit current usually starts in the form of a current rush, which then changes to the permanent short circuit current of lesser intensity (Figure 10), strong dynamic current forces occur in particular in the first few half waves of the short circuit current, and tend to open the contacts of the circuit breaker.

It is, therefore, a particularly advantageous feature, mentioned further above, that the dynamic forces occurring in the circuit breaker according to the invention during the initial half waves of a short circuit current tend to increase rather than decrease contact pressure in the breaker.

This state is illustrated in Figure 2a, in which the circuit breaker according to the invention is shown with its main and auxiliary arcing contacts in closed or "make" position.

In this position, the arrangements of a U-shaped pivotably mounted bridge 1 in combination with two separate series-connected separable contacts results in a current flow via closed arcing contacts 6, 11 the closed main contacts 1, 2 and the parallel bus bars 25 and 25a. As these elements form a U-shaped configuration there is formed a current loop. Now, it is well known that a current loop tends to widen the two parallel legs of the U-shaped configuration due to the repelling forces of the magnetic fields established by the current flow through the loop. The resultant of these loop-widening forces is a dynamic force K_{dyn} which increases the pressure of contact bridge 1 against contact members 2 and 2a (see Figures 2a and 2b). With the increased intensity of a short circuit current rush, the contact bridge is therefore pressed especially strongly against the stationary main contact members.

Only after the breaker releasing device has been actuated, do the mechanical spring forces designated by K_{mech} in Figure 2b come into play and open the contacts in such a manner that the main contacts are broken first, and become as quickly currentless as possible to avoid burning of the contact surfaces and guarantee un-

objectionable contact making and breaking over a long life time of the device.

The current then flows entirely via the still closed auxiliary arcing contacts, opening of which is briefly delayed due to the resilient nature of the stationary arcing contact members 6, 6a etc.

The formation of the electromagnetic fields in the magnetic system according to the invention are illustrated further in Figures 9 and 9a.

10 What I claim is:

1. In a circuit breaker system for electrical currents, having main contact means, an auxiliary arc-forming contact means, and magnetic arc-blowing means, the arrangement comprising two main current conducting elements, 15 a plurality of stationary main contact members and a movable contact bridge for making contact therewith and forming therewith said main contact means, at least two partial movable auxiliary contact members conductively connected to said contact bridge, and a corresponding number of stationary auxiliary contact members 20 adapted for forming arcs with said movable auxiliary contact members, when said bridge is displaced to break contact with said stationary main contact members, said bridge and movable auxiliary contact members 25 being arranged on a substantially U-shaped member with said bridge being in the region of the base of said U-shaped member and said movable auxiliary contact members being in the regions of the free ends of the legs of said U-shaped member, said U-shaped member 30 being pivotable relative to said stationary main and auxiliary contact members in such manner that said bridge moves in a space confined between said main current-conducting elements and said stationary main and auxiliary contact members, thereby ensuring a complete dynamic stability of the system.
2. The arrangement as described in claim 1, further comprising a magnetic circuit closed upon itself which provides for stray fields across the opening enclosed by the circuit, in which stray fields said auxiliary stationary 40 and movable contact members are located, said magnetic circuit replacing the conventional blow-out coil means.
3. The arrangement as described in claim 1, further comprising parallel carrier arms at one end of which said contact bridge is fastened and a shaft on which said 45 carrier arms are spacedly and insulatedly mounted for pivotable movement thereabout.
4. The arrangement as described in claim 1, further comprising a plurality of separate arc-extinguishing chambers each of which is associated with one of the auxiliary contacts formed by one stationary and the corresponding movable auxiliary arc-forming contact.
5. The arrangement as described in claim 1, further characterized in that said stationary main contact members, on the one hand, and said contact bridge, on the other hand, are adapted to effect electrical multi-point 55 surface contact with each other.
